Primary Examiner — Jae Liang*Assistant Examiner* — Jane Yoon(74) Attorney, Agent, or Firm — Jose Cherson Weissbrot(57) CLAIM

The ornamental design for a computer bag, as shown and described.

DESCRIPTION

FIG. 1 is a top, front, right side perspective view of a computer bag showing my new design;
 FIG. 2 is a bottom, back, left side perspective view thereof;
 FIG. 3 is a front view thereof;
 FIG. 4 is a back view thereof;
 FIG. 5 is a left side view thereof;
 FIG. 6 is a right side view thereof;
 FIG. 7 is a top view thereof;
 FIG. 8 is a bottom view thereof;
 FIG. 9 is an enlarged view of the portion of the computer bag encircled in FIG. 1; and,
 FIG. 10 is an enlarged view of the portion of the computer bag encircled in FIG. 2.
 The unevenly dashed broken lines in FIGS. 1-2 and 9-10, which form no part of the claimed design, encircle portions of the computer bag that are illustrated in enlargements.

1 Claim, 10 Drawing Sheets(56)
